UNITED STATES PATENT OFFICE.

EDWARD C. SMITH, OF MEADVILLE, PENNSYLVANIA, ASSIGNOR TO MEADVILLE WRENCH COMPANY, OF MEADVILLE, PENNSYLVANIA, A CORPORATION OF PENNSYLVANIA.

MACHINE FOR FORMING WRENCH-HEADS.

1,313,345.

Specification of Letters Patent. Patented Aug. 19, 1919.

Application filed July 28, 1917. Serial No. 183,344.

To all whom it may concern:

Be it known that I, EDWARD C. SMITH, a citizen of the United States, residing at Meadville, in the county of Crawford and 5 State of Pennsylvania, have invented new and useful Improvements in Machines for Forming Wrench-Heads, of which the following is a specification.

This invention relates to machines for 10 forming wrench heads and consists in certain improvements in the construction thereof as will be hereinafter fully described and pointed out in the claims.

The movable jaw of a wrench as heretofore formed has required some machining. In the present invention this is very largely, 15 if not entirely, obviated.

The wrench head is formed in a forging machine which is illustrated in the accompanying drawings as follows:

Figure 1 shows a plan view of such a machine.

Fig. 2 a plan view of the preliminary forging of a wrench head.

25 Fig. 3 a side elevation of the same.

Fig. 4 an end view of the same.

Fig. 5 a view of one of the dies for the preliminary forging operation of the wrench head.

30 Fig. 6 a plan view of such dies.

Fig. 7 a plan view of the completed wrench head.

Fig. 8 a side elevation of the same.

Fig. 9 an end view of the wrench head.

35 Fig. 10 a side elevation of one of the finishing dies.

Fig. 11 a plan view, partly in section, of the finishing dies.

Fig. 12 a side elevation of said dies.

40 The forging machine is one of ordinary construction. It has the frame 1 in which is a surrounding web 2. A longitudinal web 3 is also provided. A driving shaft 4 is mounted in bearings 5. A crank 6 is arranged on the drive shaft 4 and connected by a pitman 7 with a cross head 8, the cross head operating in guides 9 formed by the webs 2 and 3. This cross head is designed to operate a punch.

45 A plunger 10 reciprocates in guides formed by the webs 2 and 3. Cams 11 and 12 are fixed on the drive shaft 4 and operate against the rollers 13 and 14 on the plunger 10. The cams are shaped to give the plunger

reciprocating movement timed with relation 55 to the crank 6. A plunger 15 is carried by guides 16 in the webs 2 and 3 and is intended to exert sidewise pressure on the dies. The plunger 15 is actuated by a toggle lever made up of the links 17 and 18, the links being connected to the plunger 15 and the link 18 being pivotally mounted on a pin 19 on the frame. A link 20 is connected with the link 18 by a pin 21 and forms a link in a second toggle lever with a link 22, the link 22 being mounted on a pin 23 carried by the plunger 10. A yielding device is arranged in connection with the toggle levers 20 and 22, the link 22 having an arm 24 from which a link 25 extends. An arm 26 is pivotally 60 connected with the link 25, the arm 26 being carried by a pin 27 on the plunger. An arm 28 extends from the pin 27 and a link 29 extends through the frame of the machine. A spring 30 exerts pressure on the 65 link 29, thus forming a device for permitting a yielding action on the plunger 15. These parts so far as described are found in ordinary forging machines and may be varied to suit convenience.

In the initial forging operation side dies 31 are used. These dies have central faces 32 which engage the sides of the neck 33 between the jaw and guide piece of the head. The dies also have the pockets or depressions 34 and 35 for the guide ring and jaw. These are formed in opposing faces of the side dies so that when a bar is placed between the faces 32 and the side dies are brought together the bar is clamped by the side 70 pieces 32.

The end die 36 carried by the plunger 8 has a die section 37 fitting the socket 35 and also a shoulder 38 which engages the ends of the sliding blocks 38^a forming parts of the 75 dies. As the plunger 36 advances it first upsets the head 41 in the pocket 35. When the shoulder 38 engages the blocks 38^a it forces these blocks to the rear upsetting the bar and forming a guide ring 42 in the 80 pocket 34. The sliding blocks 38^a are arranged on bolts 39 (see dotted lines Fig. 6) and springs 40 (see dotted lines) return them as the plunger 36 is withdrawn. A portion of the punching is also preferably 85 accomplished in this operation, an opening 43 being formed by a punch 44 on the end of the die 37. This preliminary forging

is placed in the finishing dies shown in Figs. 10, 11 and 12. The finishing dies 45 and 46 are placed in the forging machine and are subjected to the side thrust of the plunger 15. The dies have the pockets 47 and 48 which receive and finish the jaw 41 and the guide ring 42 respectively. An end plate 49 is secured to the die 46 and has an opening 50 through which the punch 44 operates. 10 The rear end of the die 45 overlaps at 51 the die 46 and has an opening 52 in line with the opening 50 when the dies are brought together. The dies also have the faces 53 which are spaced apart so as to 15 clamp the neck 33. These faces are provided with the grooves 54 so that the metal of the neck at the edges is engaged, the groove being of a width equal to the opening 55 through the head formed as herein-after described. A punch 56 is carried by 20 the plunger 8. The punch is of the shape of the opening 55.

In the operation of the machine the blank as originally forged is placed in the finishing dies; the dies brought together, clamping the blank in place and finishing the forming of the jaw and guide ring. The overlap 51 cuts off the surplus metal. The punch is then advanced and forms the guide opening 25 in the head. The punch as it advances takes the metal between the faces of the dies, the punch passing along the groove 54 and this groove forms a guide for the punch. The punch passes through the 30 pocket 48 and through the opening 52. At the completion of the operation the head is formed having a jaw 41, the guide ring 42 and the connecting bars 33^a and 33^b, the metal being entirely removed between the 35 bars 33^a and 33^b by the action of the punch. In this way the head is practically finished 40 in a forging operation and the jaw has a double connection with the guide ring.

The important feature of the invention is 45 the bringing of the faces of the dies directly into contact or in line with the cutting edge of the punch so that all the metal the punch has to remove are the inner surfaces of the connecting bars 33^a and 33^b. Furthermore 50 the side dies are in a depression so that the rear face of the jaw has a shoulder which rests against the edge of the die and thus supports the metal of the jaw as the punch advances. The result is that the face 55 of the jaw is not distorted by the action of the punch and the finished jaw can be so

accurately finished in the forging machine as to require no machining as to the guide opening or connecting bars 33^b and 33^a or the face of the jaw.

60

What is claimed as new is:—

1. In a machine for forming wrench heads the combination of side dies forming a reduced space between sockets for the jaw and die ring of a wrench head; and a punch 65 operable between the side dies to remove material between said dies extending through the jaw and guide ring and between said dies to form a guide opening.

2. In a machine for forming wrench 70 heads, the combination of side dies forming a reduced space between sockets for the jaw and die ring of a wrench head; and a punch operable between the side dies to remove material through the jaw and guide 75 ring and extending entirely across the reduced space between the dies to form a guide opening.

3. In a machine for forming wrench heads, the combination of side dies forming 80 a reduced space between sockets for the jaw and die ring of a wrench head; and a punch operable between the side dies to remove material between said dies through the jaw and guide ring and between said dies to form a 85 guide opening, the dies forming a guide for the punch as it advances from the jaw to the guide ring.

4. In a machine for forming wrench heads, the combination of side dies forming 90 a reduced space between sockets for the jaw and guide ring of a wrench head, said dies having grooved faces; and a punch operable between the side dies to remove the material between the dies to form a guide opening, said punch moving along the groove and the groove forming a guide for the punch.

5. In a machine for forming wrench heads, the combination of side dies having 100 pockets shaped to conform to the wrench head and guide ring and an intervening narrower space for the neck between the jaw and guide ring; a punch operable between the side dies; said punch extending entirely across the space between the side dies at the 105 neck; and means for forcing the punch through the jaw socket, space between the side dies corresponding to the neck, and the guide ring socket.

In testimony whereof I have hereunto set 110 my hand.

EDWARD C. SMITH.
